NEW ARTICLE OF MANUFACTURE FOR USE
AS AN INSECTICIDE AND METHOD OF
MAKING

Harold E. Jennings, Chicago, Ill., and John M. Hutzel, Columbus, Ohio, assignors to Smithereen Company, Chicago, Ill., a corporation of Illinois

No Drawing. Application August 12, 1940,
Serial No. 352,270

6 Claims. (Cl. 167—17)

It is the object of this invention to provide means and a method of control of roaches and similar insects; and to provide a new article of manufacture and method of making which can be used for this purpose.

Heretofore in the art powdered poisons have been applied in various ways to places frequented by roaches; i. e., by shaking it from a container, by blowing the material with bellows or rubber bulb applicators and by hand or power dusters. Any of these forms of application has objectionable features incident to the raising of a dust of poisonous material, which may injure the operator, contaminate food or kitchen utensils and leave an unsightly deposit on the premises. Furthermore, it is extremely difficult to get the material limited to the exact area where the roaches can be reached with the material without spreading it over many other areas that are not desired to be covered with material.

It is the object of this invention to provide a stick or other formed piece of material which is soft enough to leave a heavy deposit of material on a wall surface to thereby secure a quick, even and neat application of the material.

It is a further object to provide such a stick that will mark both smooth and rough surfaces, leaving enough of the material, in relatively dry, powdered condition, to get on the tarsi of the roaches.

It is a further object of this invention to provide the solid mass of material in the form of a stick, cake, etc. so that it will not break, flake or get on the hands of the user and so that it will be retained in the form desired until the pressure necessary to cause the material to adhere to a surface is applied whereupon the material will be deposited on a smooth or rough surface and will adhere to the surface, while at the same time being in a sufficiently dry, powdered condition to get on the tarsi of the insects.

It is an object to provide sodium fluoride or its equivalent, in stick form, soft enough in the core to mark both smooth and rough surfaces and coated with lacquer or its equivalent, to hold it in stick, cake, etc. form.

It is a further object to provide the sodium fluoride with a binder of lubricating oil, or its equivalent, so as to cause the dust to adhere to both smooth and rough surfaces and at the same time be in powdered form so that as the roaches run over it, they pick it up on their tarsi and ingest it in their mouth parts upon cleaning their tarsi.

In detail, our invention can be practiced in a

variety of ways by which the following are typical:

Example I

In order to produce a firm stick, soft enough in the core to mark both smooth and rough surfaces, we mix 100 grams of sodium fluoride and 26 cc. of water. This mixture is pressed in the desired form such as a stick, cake, etc. The moist body so formed is then allowed to dry and is then dipped one or more times (preferably twice) in a transparent lacquer. A composition of this lacquer is:

	SOLIDS, 8%	Per cent
15	Nitro cellulose	56.25
	Dibutyl phthalate	16.25
	Ester gum	27.50

	VOLATILE LIQUIDS, 82%	Per cent
20	Ethyl acetate	30
	Toluol spirits	60
	Butyl acetate	8
	Denatured alcohol	2

25 A wide variety of lacquers may be employed even including latex solution and the like. This coating strengthens the stick, protects the applicator's hands and readily wears down without obstructing the deposit of the powder.

Example II

We have found that mixtures of sodium fluoride and lubricating oil are in some instances more effective as a powder than sodium fluoride 35 alone; for example, a powder containing six per cent by weight 30 S. A. E. motor oil. Thereafter, if desired, the material is formed in a stick, cake, etc. and lacquered or otherwise coated.

Example III

When it is desired to make a stick with a very soft core we combine 100 grams of sodium fluoride, or its equivalent, with 26 cc. of acetone. Thereafter the stick is molded. The outer surface of the stick is then hardened by dipping the stick in water for two seconds. Then a lacquer coat can be applied.

Example IV

50 Five grams of powdered rosin are thoroughly ground in a mortar with 5 grams of sodium fluoride. This mixture is thoroughly mixed into 495 grams of sodium fluoride. The resulting mixture is added to 500 cc. of water. The suspension is then allowed to settle and the supernatant liquid

is poured off until the remaining suspension is thick but fluid enough to pour. This "soup" is poured into molds and subjected to a pressure of some 500# upwards to 1000# per square inch depending upon the size of a stick. It is found desirable to compress the material in such a manner as to permit the water to escape so that the minimum of moisture would be left in the stick after the stick is pressed. The stick is then baked at a temperature of approximately 175 degrees Fahrenheit. If desired, the rosin can be eliminated.

Fundamentally, our invention is directed to the deposit of the powder by abrasion upon any hard surface by pressing, rubbing and moving the solid mass upon and over the surface to be treated.

The difficulty of the problem has been to confine the application to a predetermined area on the surface, to do so without any special apparatus such as blowers and the like, to cause it to adhere to both rough and smooth surfaces, to cause it to be deposited so that it will adhere to the surfaces but at the same time to be in a sufficiently dry, powdered condition to adhere to the tarsi of the roach. It is a further problem to incorporate in the dry material or so handle it in molding that it will have sufficient structural strength to maintain the form into which it is pressed, without interfering with its operation when deposited. One of the most difficult problems to solve has been how to hold it in this form over a considerable period to enable it to be shipped, to give it sufficient strength, to protect the applicator's hands and at the same time readily permit the material to wear down, when applied, without obstructing the deposit of the powder.

Example V

We have found that a mixture of 100 grams of sodium fluoride, 1 gram of powdered rosin and 26 cc. of water molded to form and then baked at a temperature of 174° F. will produce a satisfactory stick. The baking times vary according to the diameter of the stick as set forth in the following approximate tabulation:

Size	Diameter cm.	Average length cm.	Average dry weight grams
1.....	0.9	4.6	5.0
2.....	1.4	6.2	14.9
3.....	1.6	6.4	21.7
4.....	2.0	6.1	31.5

One of the advantages of this stick is that it need not be worn down flat at the end, but the stick can be held at an angle to the surface to which it is applied.

The rosin has two functions: it acts as a binder in forming the stick and it acts as an adhering agent for causing the adherence of the powder to the surface, particularly very smooth surfaces, which still permitting the deposit to retain its powdered form. Furthermore, it results in a smooth, hard, dustless outer surface which serves a dual function of retaining the stick in its proper form and also protecting the fingers of the users from the dust out of which this stick is composed.

If desired, the material can be colored so as to identify it and to prevent it from contaminating food.

It will be understood that this control is applicable to various species of insects such as ants, silver fish, firebrats, etc.

Furthermore, materials other than sodium flu-

oxide may be used; e. g., sodium fluosilicate, borax, boric acid, pyrethrum and various combinations of these and other materials such as oils, fatty acids and attractive substances.

5 It will be understood that we desire to comprehend within our invention such modifications as may be necessary to adapt it to varying conditions and uses.

Having thus fully described our invention, 10 what we claim as new and desire to secure by Letters Patent, is:

1. As a new article of manufacture, a non-melting insoluble insect control material consisting substantially completely of poisonous sub-

15 stance comprising a molded body of sodium fluoride and water, said body having a lacquer coating applied after molding, said lacquer coating forming an inedible, non-poisonous, non-melting, non-dusting, insoluble film thereon, said 20 molded body having a powdery core and a relatively hard outer surface.

2. The method of manufacturing a non-melting insoluble insect control body consisting substantially completely of poisonous material comprising molding a mixture comprising 100 parts by weight of sodium fluoride, 1 part by weight of powdered rosin and 26 parts by weight of water, and baking the molded mixture at substantially 174° F. to form a molded body with a dustless, 25 inedible, non-melting, poisonous retaining surface, said surface being relatively hard as compared with the core of said molded body.

3. The method of manufacturing a molded non-melting insoluble insect control material 30 consisting substantially completely of poisonous material and having a powdery core and a relatively hard outer surface which comprises mixing substantially 100 parts by weight of sodium fluoride and substantially 26 parts by weight of

35 water, molding the mixture, drying the molded material, and then coating it with a liquid composition adapted to form an inedible, non-poisonous, non-melting, non-dusting insoluble film thereon.

4. The method of manufacturing a molded insect control material consisting substantially completely of poisonous material and having a powdery core and a relatively hard outer surface according to claim 3 in which the liquid coating 40 composition consists of substantially 8% solids consisting of nitrocellulose 56.25%, dibutyl phthalate 16.25% and ester gum 27.50% and substantially 82% volatile liquid consisting of ethyl acetate 30%, toluol 60%, butyl acetate 8% and denatured alcohol 2%.

5. The method of manufacturing a molded non-melting insoluble insect control material 45 consisting substantially completely of poisonous material and having a powdery core and a relatively hard outer surface which comprises mixing substantially 94 parts by weight of sodium fluoride and substantially 6 parts by weight of light lubricating oil, molding the mixture, and coating the molded material with a liquid composition 50 adapted to form an inedible, non-poisonous, non-melting, non-dusting, insoluble film thereon.

6. The method of manufacturing a molded non-melting insoluble insect control material 55 consisting substantially completely of poisonous material and having a powdery core and a relatively hard outer surface which comprises grinding together 5 parts by weight of rosin and 5 parts by weight of sodium fluoride, adding to said 60 grind 495 parts by weight of sodium fluoride and 50 parts by weight of water to form a suspension,

allowing said suspension to settle, removing the supernatant liquid leaving a thickened slurry or "soup," pouring said "soup" into a mold and subjecting it to a pressure of from 750 to 1000 pounds per square inch while permitting excess water to flow out of the mold, removing the molded material from the mold, and baking it at substan-

tially 175 degrees F., whereby a molded article is produced having a hard non-dusting, non-melting and insoluble outer surface and a comparatively soft core.
